Inventor:
Edgar F. Collins,
by *Albert G. Davis*
His Attorney.

UNITED STATES PATENT OFFICE.

EDGAR F. COLLINS, OF SCHENECTADY, NEW YORK, ASSIGNOR TO GENERAL ELECTRIC COMPANY, A CORPORATION OF NEW YORK.

ELECTRIC FURNACE.

Application filed May 18, 1921. Serial No. 470,624.

To all whom it may concern:

Be it known that I, EDGAR F. COLLINS, a citizen of the United States, residing at Schenectady, county of Schenectady, State of New York, have invented certain new and useful Improvements in Electric Furnaces, of which the following is a specification.

The present invention relates to electric furnaces and comprises in particular an improvement in the packing surrounding the part of the electrode passing through a furnace wall.

Heretofore a water-cooled member was used as a casing about the part of the electrode entering the furnace wall. In accordance with my invention I have simplified the electrode packing by providing a refractory sleeve of relatively good heat dissipating capacity which does not require artificial cooling.

My invention is illustrated by the accompanying drawings, Fig. 1 showing a vertical section of an arc furnace embodying my invention and Fig. 2 being a vertical section of the electrode sleeve and adjacent supports.

Referring to the drawing, the arc furnace here illustrated comprises a walled container 1, adapted to contain a molten charge upon a hearth 2, a plurality of electrodes projecting through the arched roof 3, two only being shown, designated as 4 and 5. The upper electrodes, which preferably are movable, operate with electrodes on the furnace hearth as shown at 6, these lower electrodes being joined by a conductor 7. Surrounding the portions of the electrodes 4, 5 adjacent the roof 3 but external thereto are sleeves 8, 8' consisting of a refractory heat conductive material. In a preferred embodiment of my invention the sleeve is made by molding finely divided carborundum with a suitable binder.

In Fig. 2 I have shown the sleeve 8 surrounded by a shell 9 consisting of iron or the like and forming part of a spider 10 which is bolted to brackets 11 upon the furnace side wall 12, and which supports devices not shown in the drawing. The shell 9 acts as a mechanical support and as a heat radiator during the operation of the furnace. In some cases, the sleeve 8 may be

molded by ramming a mixture of the refractory material and a plastic binder into the shell 9, a suitable removable spacer surrounding the electrode. The usual current 55 conducting terminals may be connected to the exposed ends of the electrodes 4, 5.

The heat conductivity and relatively large mass of the sleeves 8, 8' results in a sufficient heat dissipation to insure cooling the 60 electrodes at the portions exterior to the furnace housing to a temperature low enough to preclude wasting away by oxidation.

It sufficiently appears from the illustrated embodiment of my invention that it is applicable to furnaces other than arc furnaces, but it is particularly valuable for this type of furnace because of the high temperature to which the electrodes are subjected in the furnace interior. 70

What I claim as new and desire to secure by Letters Patent of the United States, is,—

1. An electric furnace comprising a housing, an electrode projecting through said housing, and means for dissipating heat 75 from the portion of said electrode external to said housing including a sleeve made of refractory material having a relatively high heat conductivity surrounding said electrode. 80

2. An electric arc furnace comprising a housing, a carbonaceous electrode projecting therethrough and a carborundum sleeve surrounding said electrode immediately adjacent said housing and exterior thereto. 85

3. An electric furnace comprising a container, an electrode projecting therethrough, a sleeve of refractory material surrounding said electrode and projecting outwardly from said container and a metal shell surrounding 90 said refractory sleeve.

4. An electric arc furnace comprising a container, an arc-supporting electrode movably passing therethrough, a sleeve comprising a refractory carbide surrounding said 95 electrode over a portion external to and adjacent said container, and a heat radiator surrounding said sleeve.

In witness whereof, I have hereunto set my hand this 17th day of May, 1921.

EDGAR F. COLLINS
